Primary Examiner — Calvin E Vansant*Assistant Examiner* — Benjamin L. Gray(74) *Attorney, Agent, or Firm* — Buchanan Ingersoll & Rooney PC(57) **CLAIM**

The ornamental design for a handle as shown and described.

DESCRIPTION

FIG. 1 is a top right side isometric view of a handle showing our new design;

FIG. 2 is a right side elevation view thereof;

FIG. 3 is a left side elevation view thereof;

FIG. 4 is a front elevation view thereof;

FIG. 5 is a rear elevation view thereof;

FIG. 6 is a top plan view thereof; and,

FIG. 7 is a bottom plan view thereof.

The broken line showing of the handle is for the purpose of illustrating portions of the handle and forms no part of the claimed design.

1 Claim, 5 Drawing Sheets(56)
